U.S. Cl. D8—62

FIG. 1 is a side view of this portable grinding machine showing my new design;

FIG. 2 is a top view;

FIG. 3 is a bottom view;

FIG. 4 is a rear end view; and

FIG. 5 is a front end view of this portable grinding machine.

The opposite side of the portable grinding machine not shown in the drawing has an appearance identical with the appearance of the side view shown in FIG. 1 of the drawing.

The dominant features of my design reside in the portions shown in full lines.

I claim:

The ornamental design for a portable grinding machine, substantially as shown and described.
